CLAIM

The ornamental design for a container for pouches of smokeless tobacco, as shown and described.

DESCRIPTION

FIG. 1 is an exploded perspective view of a container for pouches of smokeless tobacco with the lid and base separated, showing our new design;

FIG. 2 is a top plan view thereof without the lid;

FIG. 3 is a side view thereof without the lid;

FIG. 4 is a side view thereof with the lid; and,

FIG. 5 is a top plan view of the container, shown without the lid and illustrating the pouches of tobacco ready for use. The broken lines in FIG. 5 showing pouches of smokeless tobacco in the container is included for the purpose of illustrating environmental subject matter only and forms no part of the claimed design.
